UNITED STATES PATENT OFFICE.

EDWARD H. CHAPMAN, OF BETHLEHEM, PENNSYLVANIA.

TUBE-MILLING MACHINE.

Application filed September 9, 1919. Serial No. 322,614.

To all whom it may concern:

Be it known that I, EDWARD H. CHAPMAN, a citizen of the United States, residing at Bethlehem, in the county of Northampton, 5 State of Pennsylvania, have invented a new and useful Tube-Milling Machine, of which the following is a specification.

This invention relates to the class of machines which are adapted to mill the ends of tubes, particularly the water tubes of boilers of which, for instance, the "Yarrow" boiler is a type,—taking them in rough stock lengths and bringing them to predetermined lengths, for example, the exact length required for insertion in the drums of particular boilers.

In operating my milling machine, I have had in contemplation and have in part illustrated its application to an annealing furnace of a type suitable for the purpose.

The principal object of my invention is an organized machine in which any plurality of tubes the ends of which it is desired to mill,—that is, cut off, reamed or threaded, are 25 one by one and rapidly fed to the milling mechanism, and, after being milled, are one by one and rapidly transferred from the machine either to a furnace when it is in contemplation that the milled tubes shall be annealed or otherwise treated, or else to an ultimate receptacle in which they are to be deposited.

To the foregoing principal end, my invention comprehends an organized machine in 35 which there are assembled in co-acting relationship certain elemental instrumentalities which include the following:—

Means for feeding tubes to be milled to the milling devices,—means for receiving each tube as fed and securing it in place to have its ends milled,—means for milling by simultaneous operation both ends of the tube as secured in place,—means for end-wise adjustment of the milling means,—means for actuating the milling means to effect their operation simultaneously and, preferably, in reverse directions upon both ends of the tubes,—means for removing each tube after having been milled, from the 45 means which secure it in place to be milled,—means for operating the securing means, the milling means, and the removing means,—means to permit of the removal of the milled tube from the machine,—and, in conjunction

therewith, a furnace, or other ultimate receptacle.

Such being the general organization of my elemental means, I prefer to employ for feeding the tubes, inclined guide brackets down which they roll in successive order to the milling devices.

Further, I prefer to employ similarly organized or counterpart, but oppositely disposed vertically mounted cylinders the pistons of which, subject to fluid control, co-operate with clamping or holding devices which retain the ends of the tubes in juxtaposed alignment with the milling heads,—and also to employ milling heads, similarly counterpart and oppositely-disposed, which under the control of pistons of horizontally and oppositely-disposed cylinders, and also of means for rotating them, are forced against both ends of the tube so as to effect the milling,—employing for the control of the pistons of both sets of cylinders, a valve mechanism for the motive fluid.

Further, I prefer to employ means for controlling both milling heads simultaneously but preferably to opposite rotation, so as to secure effective and uniform oppositely applied end-milling.

Further, I prefer to employ means co-operating with the holding means of the vertical cylinders, to effect the release of the tubes one by one after they have been milled and permit of their discharge from the machine.

For the purpose of illustrating my invention I have shown in the accompanying drawings a certain type and embodiment of it which is at present preferred by me because in practice it has given satisfactory and reliable results.

It is to be understood, however, that the various instrumentalities in which my invention is shown as embodied, can be variously arranged and organized, and that my invention is not, therefore, limited to the precise arrangement and organization illustrated and typified in the constructions represented in the accompanying drawings and herein described.

In the accompanying drawings, Figure 1 represents a front elevation of a milling machine embodying a preferred organization of my invention.

Figure 2 represents a top plan view of

the machine of Figure 1,—a typical heating furnace being represented in association therewith, to illustrate in a general way how my milling machine may be connected with a furnace.

Figure 3 represents an end elevation from the right-hand side of my machine and of the typical furnace represented in Figure 2.

Figure 4 represents a central, sectional, 10 side elevation through the left-hand vertical cylinder, the left-hand horizontal cylinder, the driving gears of the left-hand milling head, and the general mounting of these elements with relation to the bed of the machine,—certain of the parts being shown in elevation.

Figure 5 represents an inside end elevation of the vertical cylinder shown in Figure 4, illustrating also its supporting standard 20 and bed plate, a bracket bearing for the driving shaft, the clamping control and the release devices connected respectively with the vertical piston and the vertical cylinder,—the clamp block 31 of Figure 4 and a 25 portion of the tube resting upon it being omitted, and the scale being slightly different.

Figure 6 represents a plan of Figure 4, illustrating particularly the vertical cylinder, the head bearing, the bed plate and in 30 central and longitudinal section the bearing 13 for the milling head shaft 9.

Figure 7 represents in enlarged detail, a 35 horizontal section on the line 7—7 of Figure 4, of the horizontal cylinder 21, its piston and part of the milling head shaft being shown in plan.

Figure 8 represents in central, horizontal 40 plan an eight-way valve of the character which I prefer to employ in connection with the motive fluid pipe line system which I prefer to make use of for the predetermined control of the vertical pistons and of the horizontal pistons.

Figure 9 represents a section on the line 45 9—9 of Figure 8, of one of the positions of the valve and its ports.

Figure 10 similarly represents a section on the line 10—10 of Figure 8, of another 50 position of the valve and ports.

Figure 11 similarly represents in section on the line 9—9 of Figure 8, another of the positions of the valve and ports.

Figure 12 similarly represents in section 55 on the line 9—9 of Figure 8, another of the positions of the valve and ports.

The several positions indicated in Figures 9, 10, 11 and 12, and the service which the valve performs in them, are hereinafter 60 fully explained.

Similar numerals and letters of reference indicate corresponding parts.

Referring now more particularly to the first three figures of the drawings,—1 design-

nates the bed of the machine, erected upon 65 pedestals 2 and 3. Upon the left-hand end of the machine a motor base 4 is supported from the pedestal 2 by a brace 5 or similar supporting device, and upon the shaft of the motor 4 is mounted a driving pinion 6 in 70 mesh with a driven gear 7 mounted upon the left-hand end of a driving shaft 8 paralleling the bed of the machine and suitably housed for rotary movement below its top level. The driving pinion 6 and driven 75 gear 7 together form a reduction gear for the motor driven machine considered as an entirety.

The milling machine operates simultaneously upon both ends of the tube T to 80 be milled, through the instrumentality of counterpart milling heads 9 and 10, the construction of which is hereinafter referred to and illustrated in detail in Figures 4, 5 and 7.

The milling heads are, one or both, adjustable endwise upon the bed to adapt them to operate upon any length of tube, by being so organized and applied to the bed as to be adapted to traverse it a given distance lengthwise in opposing directions.

The milling heads 9 and 10 are respectively mounted upon milling head shafts 9* and 10*.

Each milling head shaft is driven by a 95 driven spur wheel 11, feathered upon it and in mesh with a driving pinion 12 on the driving shaft 8.

Each milling head shaft is housed in a bearing 13 erected from a longitudinal bed 100 plate 14 or 15, which are adapted, one or both, the right-hand bearing alone as illustrated, to travel in slide ways 16 upon the bed of the machine. In addition to the support of the bearings 13, each milling head shaft is housed in connection with a head bearing 18 in a vertical standard 19 which supports a vertical air cylinder 20, and is also housed in a ball-bearing formed within a horizontal air cylinder 110 21,—all as shown in the detailed drawings Figures 4, 5, 6 and 7, and hereinafter more particularly described.

Inasmuch as the driven gears 11 are feathered upon the milling head shafts, it 115 will be obvious that the milling heads, the vertical air cylinders, the horizontal air cylinders and the bearings for the shafts, as well as said gears 11, can, one or both as an assemblage, be moved with relation to the bed so as to be brought together or separated given distances, to adapt the milling heads to operate upon any length of tube to be milled.

The operation of the milling heads by 125 the action of the pistons of the horizontal air cylinders hereinafter described, is such as to force them against the ends of the

tubes, the length of travel being regulated by collars 22, as particularly shown in Figure 1.

In order to effect the desired reverse rotation of the milling heads upon the ends of the tubes, I divide the driving shaft 8 into two parts, by the interposition of reversing bevel gears which I have designated 23, and which in the general mode of construction and application to the bed of the machine, I have particularly illustrated in Figures 1 and 2.

This reversing bevel gear functions solely to effect the reverse rotation of the two divided ends or end portions of the driving shaft 8, in order that a driving pinion 12 rotating in one direction with one end of the shaft may drive its driven spur wheel 11 in one direction, while a counterpart driving pinion 12 on the other end of the shaft will drive its driven spur wheel 11 in the opposite direction, with the result already mentioned that the two milling head shafts will be rotated in reverse directions to occasion the opposite rotation and action of the milling heads.

Still confining myself to the general assembly of my machine as illustrated in Figures 1, 2 and 3, and employing selected numerals to designate particular generic parts or elements of the machine as an entirety, which elements are particularly illustrated in the drawings commencing with Figure 4 and ending with Figure 12,—

24 designates an air valve reversing gear, which, through a system of levers and connecting rods designated, particularly in Figure 2, as 25, 25¹, 25², 25³, 25⁴ and 25⁵, operates upon both the vertical air cylinders 20, which are provided with tube-clamping controls designated 26 and with release or knock-off devices designated 27, and together control the lifting and release of the tubes,—and also upon the horizontal air cylinders which control the advance and retraction of the milling heads and operate subsequently to the operation of the vertical air cylinders,—all as hereinafter described.

28 designates typical runways upon which the tubes after being milled are deposited and permitted to roll gravitatively on to a conveyor system 29 operating in conjunction with any furnace that may be employed in connection with my milling machine.

53 When the tubes are brought to my milling machine they are first deposited upon guide brackets 30 particularly illustrated in Figures 2 and 3, which are supported by any preferred bracing connecting them with the bed of the machine, their disposition relatively to the bed being angular, so the tubes roll down them until they reach and rest upon longitudinally recessed or guttered clamp blocks 31 erected upon the bed plates 14 and 15, upon which, as already explained,

the milling shafts and their adjuncts are mounted.

When a tube has been thus deposited upon the clamp blocks, the next operation is to secure it in place by the descent of the pistons within the vertical cylinders, the clamping controls 26 holding it in place until, at the next operation, the pistons of the horizontal air cylinders are forced forward and the milling heads through their pinions 12 and spur wheels 11 thrown into action to effect the milling.

The system of levers and connecting rods designated 25 to 25⁵, as already mentioned, typically illustrated in the first three figures, 80 is actuated by a controlling disc 32, centrally mounted upon the bed of the machine and sufficiently illustrated in said figures.

Extending transversely beneath the bed is a worm shaft 33, the mounting of which with reference to the bed is illustrated in Figures 1 and 2, which is provided with a universal joint connection 34 to a link shaft 37, upon the opposite side of the bed, and which is actuated to the desired rotation by 90 being operatively connected with a worm 35 on the driving shaft 8.

A supplemental worm gearing 36 at the outer or distant end of the connecting device which I have termed a link shaft 37, occasions the predetermined rotation of a conveyor shaft 38 housed in relation to the front of a typical furnace and serving to support and rotate conveyor sprockets 39 which by means of parallel conveyor chains 40 are 100 connected with counterpart sprockets 41 on a counter shaft 42 supported at the rear of the furnace. The function of this conveyor as an entirety is to convey to a furnace the tubes to be annealed, if the furnace be an annealing furnace, or to be otherwise treated if the furnace be of another type, and it serves simply as a means of physical conveyance of the milled tubes as successively deposited upon it across the furnace,—and is, of course, adapted to deposit the milled tubes upon any receiving device such as a platform or truck.

To the extent that I have thus far described my invention and incidentally in a sufficiently explanatory way its mode of operation, I have treated it and its component elements and their adjuncts as a typical organization, and although as I have already explained, I do not confine myself to the 115 specific forms and constructions of the operating elements, I have in practice found that certain types of them are well adapted for my purpose and I will therefore now describe typical and preferred embodiments 120 of the elements themselves.

Referring, first, to the counterpart assemblies of vertical and horizontal cylinders, milling heads, milling head shafts and means for rotating, advancing and retract- 125

ing the milling heads, I have in Figures 4, 5, 6, and 7 illustrated a preferred embodiment of said elements, selecting that which in the first three figures of the drawings is ⁸ that shown at the left-hand end of the bed.

I have selected this embodiment because except in the detail of mounting for longitudinal in and out movement upon a sliding bed plate movable in slideways, to bring the ¹⁰ milling heads more closely together or further apart to adapt them to operate upon tubes of different lengths,—which is that shown at the right-hand of the organization of the first three figures,—the two organizations or embodiments are counterparts.

Premising that the fluid control which operates upon the pistons of both of the vertical cylinders and upon the pistons of both of the horizontal cylinders, is controlled by ²⁰ a valve of, for instance, the typical organization shown in Figures 8 to 12 and later explained, I desire it understood that the cylinders shown and described are typical cylinders merely well adapted for my purposes and that other types may be substituted for them.

The typical vertical cylinder 20, Figures 4, 5, and 6, contains a vertical piston 20^x, the outwardly-extending lower end of which is ³⁰ formed or provided with a transversely extending exterior head, which is bifurcated at its end nearest the vertical standard 19 and so as to be adapted to travel upon a guide web 19^x extending forwardly from ³⁵ and being a part of the vertical standard 19, this being an arrangement intended to prevent possible rotation of the piston within its cylinder.

At their ends furthest from the standards, ⁴⁰ these heads have attached to them the clamping controls 26, which are conveniently merely a pair of spring clips, the lower oppositely curved ends 44 of which are adapted to be sprung upon a tube resting upon the ⁴⁵ clamp blocks 31, when the pistons descend, and which co-operate with clamping blocks 45 which are longitudinally cylindrically recessed to make them match with the upturned correspondingly but oppositely recessed carrying heads 31^x, of the clamp blocks 31.

In the operation of securing a tube to be milled upon the clamp blocks 31, the descent of the pistons 20^x not only through the ⁵⁵ clamping blocks 45 and the curved ends of the clamping controls, effects the holding or securing of the tube, but also, after the milling has been completed, in the elevation of the piston assures the lifting of the tube ⁶⁰ from the clamp blocks 31, through the agency of the clamping controls, up to a point when the tube encounters the release devices 27 on the cylinders which force the tube free from the clamping controls and

permit of its rolling off upon the runways ⁶⁵ 28.

The release device 27 is simply a depending knock-off bar rigidly bolted to the front face of each vertical cylinder 20 as shown in ⁷⁰ Figures 4 and 5.

The reciprocation of the vertical pistons under the influence of the valve hereinafter described, which controls the motive fluid from a source of supply, utilizes a differential pressure area which in the embodiment ⁷⁵ illustrated is greater at the top of the vertical cylinders and less below.

The upper vertical piston packing 46 is confined by a nut 47, which results in the ⁸⁰ area 48, Figure 4, above the packing being greater than the cylindric area 49 which surrounds the piston within the cylinder, and within which last named area the motive fluid is constantly contained.

In Figure 4, 50 designates the lower piston packing which may, if desired, be of the ⁸⁵ special form shown in connection with the outer end of the horizontal piston 21^x particularly illustrated in Figure 7.

Referring now to the horizontal cylinder ⁹⁰ 21 shown in preferred detail in Figure 7, the horizontal piston is designated 21^x, and the special construction that I prefer to employ is the following:

The piston itself being of less diameter ⁹⁵ than the interior of the cylinder so that a cylindric area 51 exists around it,—the rear stuffing box is conveniently composed of a pair of washers 52 between which is a separating disc 53 and behind which is a nut 54 ¹⁰⁰ threaded upon a rearwardly extending stem 55 of the piston which by being screwed inwardly compacts the washers to close any leakage of motive fluid.

In the detail of this stuffing box it will be ¹⁰⁵ observed that the piston is formed with a circumferential shoulder 56 diametrically fitting within the cylinder, and that it is somewhat reduced at its inner end as at 57 to permit of the outer washer being folded ¹¹⁰ over it so as to present a broad surface of contact with the interior of the cylinder, as in similar manner the inner washer folds over the clamping nut 54.

At its front end the horizontal piston 21^x ¹¹⁵ is chambered as at 58 and at 59, to receive the inner end of the milling head shaft 9^x, which is rotatable upon two confined ball races 60 and 61 within the outer chamber 59, which races are secured by a nut 62 screwing ¹²⁰ within the piston chamber 59.

The outer end of the horizontal cylinder is provided with a stuffing box composed of an inturned washer 63 which is confined by a cylinder head 64 against a ring 65 internally recessed to receive the inturned part of the washer 63, and which through the force of head-retaining nuts 66 is itself ¹²⁵

As already referred to in connection with the vertical pistons, the reciprocation of the horizontal pistons is under the influence of a valve which controls the motive fluid from its source of supply, and utilizes a differential pressure area which, as illustrated, is greater at the inner end of the cylinder and less at the outer end, the area 68 at the inner end of the cylinder beyond the packing washers 52, being greater than the cylindric area 51 which surrounds the piston within the cylinder, and within which last named area the motive fluid is constantly contained.

The inlet port of the cylinder and its outlet port into which respectively lead the pipe lines a^2 and b , are illustrated in Figure 7 in connection with the horizontal cylinder shown and respectively connected with the pipe line system hereinafter explained.

20 In Figure 4 the bracket bearing 8* which carries the left-hand end of the shaft 8 is particularly illustrated, and is preferably integral with the bed plate 14 with which the bearing 13 for the milling head shaft 9* 25 and the vertical standard 19 are also integral.

In Figure 4 there are also represented the feather 69 within the hub of the driven spur wheel 11 and the featherway 70 on the milling head shaft 9*. In addition, there is 30 reperesented the socket 71 for the milling tool of whatever type may be used.

Referring now to Figures 8 to 12 inclusive, 35 72 is a cylindrical valve casing which is shown in Figures 1 and 2 as supported below the bed of the machine and as extending transversely thereof.

The valve of this casing, the tapered body of which within said casing is designated 40 73 and the hollow tubular interior 76, is, in the organization shown, at its end which is nearest to the furnace or delivery side of the milling machine proper provided with a valve crank 74 connected with the connecting rod designated in Figure 2 as 25*, and which 45 extends to the right hand end of the machine and is connected with a crank 25' on the rear end of a crank shaft 25* which on its front end is provided with a crank 25* which is operated by the connecting rod 25, Figures 1 50 and 2 and the distant end of which is coupled to a wrist pin 25* which plays in a segmental slot 24* in what I have termed an air-valve-reversing-gear 24, the same being a disc on the worm shaft 33 as best shown 55 in Figure 1.

Obviously, in the rotation of the driving shaft 8, the rotation of the worm 35 will, by its operative connection with the worm shaft 33, occasion the rotation of the said 60 worm shaft and also the rotary movement of the air-valve-reversing-gear 24, which gear, by the calculated length of the slot 24*, will through the wrist pin 25*, occasion such calculated throw of the connecting rod 65 25 as, through the crank shaft connection

25*, will occasion the calculated throw of the connecting rod 25* and through it the calculated oscillation of the valve crank 74 and the consequent calculated rotary movement of the tapered valve 73 within the valve casting 72. 70

In Figure 8, I have shown a stuffing box connection for the valve, with the nipple or inlet end 75 through which the motive fluid from the source of supply enters within the 75 hollow tubular interior 76 of said valve, and this stuffing box which is intended to permit of the rotary movement of the valve body relatively to the nipple or inlet member 75 is conveniently of the following construction: 80

77 is a hollow threaded cap stuffing box, which by means of its threads is securely affixed to the threaded outlet end of the tapered body 73 of the valve, and which serves within its hollow extended interior to confine the packing 78 against the outer wall of the nipple end 75, which nipple end is at its inner end formed with a flange 79 upon which the packing 78 rests and is 90 forced down by a tubular thimble 80 which surrounds the nipple end and is itself held in place by a compression cap 81 screwing upon the outer threaded wall of the threaded stuffing box 77. 95

By this means the entire stuffing box constitutes a swivelling expansion joint for the rotary valve casing.

The retention of the valve proper 73 with relation to the casing 72 is conveniently effected by the compression of a nut 82 which forces a washer 83 down upon the end of the valve casing, as shown in Figure 8. 100

As already explained, this valve is preferably an eight-way valve, although two 105 four-way valves properly mounted and applied would perform a similar function, and it is illustrated in detail by a comparison of the sectional views Figures 9, 10 and 11 and 12 with the view of Figure 8. 110

The function of this valve in the oscillatory rotary movement imparted to it by the reversing gear 24, is four-fold:—first, to supply motive fluid to depress the vertical pistons to secure the tube in position upon the 115 machine to have both of its ends simultaneously milled;—second, to supply motive fluid to propel outwardly and oppositely towards each other, the horizontal pistons so as to force the milling heads against the ends of the tube to be milled,—this operation taking place while the vertical pistons are serving to hold the tube in position;—third,—to supply motive fluid to propel inwardly and away from each other the horizontal pistons so as to release the milling heads from against the ends of the tube after it has been milled,—this operation taking place while the vertical pistons are still serving to 120 secure the tube in position;—and, fourth;— 125 130

to supply motive fluid to elevate the vertical pistons so as to lift and release the tube from its secured position upon the machine so as to permit of its movement away from the machine.

Of course, in the performance of these successive functional and cyclical steps of the operation, the motive fluid must be first simultaneously let into the larger pressure areas within both of the vertical cylinders, and for the time being and after it has served downwardly to propel the vertical pistons must be retained within said cylinders before the lead is given to the exhaust from their larger pressure areas;—then, the motive fluid must be simultaneously let into the larger pressure areas within both of the horizontal cylinders so as to propel the pistons outwardly and must be retained therein until the milling heads have done their work before the lead is given to the exhaust from said larger pressure areas of said horizontal cylinders;—then, the lead being given to the exhaust from the larger areas of said horizontal cylinders, the motive fluid within the smaller pressure areas of said cylinders will occasion the reverse movement of the pistons to withdraw the milling heads;—and, lastly, the lead being given to the exhaust from the larger pressure areas of the vertical cylinders, the motive fluid within the smaller pressure areas of said cylinders will occasion the upward movement of the vertical pistons successively to lift and release the tubes after their heads have been milled.

Each one of the foregoing successive steps of operation is effectually and satisfactorily performed by the oscillation, predeterminedly controlled, of my eight-way valve, and a reference to the sectional views of Figures 9, 10, 11 and 12 of my valve, and to the diagrammatic view of my motive fluid pipe system shown in Figure 2, will indicate the different positions which the valve assumes in controlling the motive fluid to the above described ends.

Referring to Figure 2, I have, for clearness, used the letters a , a' , a^2 and a^3 , and also the letters b , b' , b^2 and b^3 , to designate the motive fluid pipe lines which respectively connect with the several ports of the valve cylinder 72 which are respectively indicated in the planes of the dotted lines 9—9 and 10—10 of Figure 8 and in given planes and positions of the ports in Figures 9 to 12 inclusive.

To further explain: The first operation of supplying motive fluid to depress the vertical pistons is accomplished when the ports of the valve with relation to the ports of the valve casing are in the positions represented in Figures 9 and 10, which may be considered as typifying the other views of Figures 11 and 12,—in which the inlet ports c , c' are in registry with the ports d , d'

of the casing, Figure 10, which ports, respectively, are connected with the pipe line a and a' , so that the motive fluid entering the tubular interior 76 of the valve will simultaneously flow through the pipe lines a and a' to the larger pressure areas 48 of the vertical cylinders to depress their pistons,—while, simultaneously, the ports c^2 and c^3 of the valve (Figure 9) will be in registry with the ports d^2 and d^3 of the casing, which ports, respectively, are connected with the pipe line b^2 and b^3 and with the exhaust ports d^4 and d^5 , Figure 9,—so that said pipe lines b^2 and b^3 will be exhausting.

While the foregoing operation or movement of the motive fluid is taking place by reason of the positioning of the ports represented in Figures 9 and 10, the ports which connect with the pipe lines other than a , a' and b^2 and b^3 , will be in the positions respectively represented in Figures 11 and 12.

In order that the operation may be understood without unnecessarily increasing the number of figures of the drawings to show every position of the valves relatively to inlet and to exhaust, I have confined my illustration to the four cross sections, Figures 9, 10, 11 and 12, and have not illustrated every position of the valve in which certain of the inlets and certain of the exhausts are out of service or in neutral positions, so to speak.

The second operation which is that of supplying the motive fluid simultaneously to the larger pressure areas 68 of the two horizontal cylinders, so as to propel inwardly and oppositely the horizontal pistons to drive the milling heads into action, takes place when the valve is in the position represented in Figure 9, in which the inflowing motive fluid which is to feed the pipe line a^2 and a^3 , and close the pipe line b^2 and b^3 , as well also to permit of the exhaust through the pipe lines b and b' , passes to said pipe lines a^2 and a^3 and through them, as indicated in Figure 2, into the larger pressure areas 68 of the horizontal cylinders.

Obviously, that this operation may take place, the closing of the flow into the vertical cylinders must be effected and the exhaust therefrom neutralized.

During this operation, therefore, while lines a^2 and a^3 and lines b , b' are open, lines a , a' and b^2 , b^3 , are closed, a result directly due to such placement of the valve as is represented by its position in Figure 10.

The third operation which is that of exhausting the motive fluid from the larger pressure areas 68 of the two horizontal cylinders so as to permit the motive fluid within the smaller pressure areas 51 of said cylinders to operate to propel outwardly and oppositely away from each other the horizontal pistons to retract the milling heads from the ends of the tube, takes place when the valve is in the position represented

in Figure 12, and in which the inflowing motive fluid which is to be fed through the pipe lines b and b' is alone operative, the pipe lines a^2 and a^3 being open to permit of the 5 exhaust from the larger areas 68 of said cylinders, while the pipe lines a , a' and b^2 , b^3 are closed by reason of such placement of the valve as will occlude both inlet and exhaust ports, for the time being as such, 10 of said pipe line.

The fourth operation which is that of supplying motive fluid simultaneously to the smaller pressure areas 49 of the two vertical cylinders so as to permit of the elevation of 15 the vertical piston and the lifting of the tubes from the machine, while permitting the exhaust from the larger pressure areas 48 of said cylinders, takes place when the valve is in the position shown in Figure 11, 20 in which the motive fluid is flowing through the pipe line b^2 and b^3 and exhausting through the pipe lines a , a' , while at the same time the pipe lines a^2 , a^3 and b , b' , are closed by the then placement of the valve 25 with respect to its other inlet and exhaust ports.

Of course, the foregoing operations may be performed in the predetermined and desired order by a valve of a different 30 character than the precise eight-way valve I have shown and described,—or it may be performed by two four-way valves,—but that which is material is the performance 35 itself, and I do not, therefore, desire to limit myself to the precise form of valve organization as applied to a pipe-line motor-fluid system such as I have typically represented as connected with the two vertical cylinders and the two horizontal cylinders.

40 Thus, while I have shown my valve as geared through the connection of the air-valve-reversing-gear 24, itself operating through the worm shaft 33 and worm 35 from a direct connection with the driving 45 shaft 8, itself controllably driven from the motor,—with the system of levers and rods 25, 25¹, 25², 25³, 25⁴ and 25⁵, I do not confine myself to such a connection, because my 50 broad idea is simply to control a valve connected with a pipe line system for a motive fluid supply and control, by means so timed, if not directly connected with the driving mechanism of the milling heads, as will ensure the proper cyclical movement 55 of the several pistons with respect to the movements of the milling heads.

Thus, further, my invention is broad enough to comprehend any means for the desired predetermined control of the movements of the several pistons with relation to the movements of the milling heads.

60 I believe, of course, that a motive fluid supply under proper valve control is the practical and best way of doing the work, 65 but I do not confine myself to it as the only

means by which the several pistons may be co-ordinately operated,—any more than I desire to limit myself to a reverse movement, as opposed to a direct or similar movement, of the milling head shafts and milling 70 heads.

These details do not reach the essence of the invention and are obviously within the judgment of the constructor.

It will now be apparent that I have 75 devised a novel and useful construction of a tube milling machine, which embodies the features of advantage enumerated as desirable in the statement of the invention and the above description, and while I have, in 80 the present instance, shown and described a preferred embodiment thereof which will be found in practice to give satisfactory and reliable results, it is to be understood that the same is susceptible of modification in 85 various particulars without departing from the spirit or scope of the invention or sacrificing any of its advantages.

Having thus described my invention, what I claim as new and desire to secure by Letters Patent, is:—

1. In a machine of the character stated, means for clamping a tube in position to be milled, oppositely rotatable devices for milling the ends of said tube, and fluid pressure 95 controlled mechanism for advancing and retracting said milling devices with respect to the ends of said tube.

2. In a machine of the character stated, means for clamping a tube in position to be milled, devices for milling the ends of said tube, and fluid pressure controlled mechanism for advancing and retracting said milling devices with respect to the ends of 100 said tube.

3. In a machine of the character stated, fluid pressure controlled means for clamping a tube in position to be milled, devices for milling the ends of said tube, and fluid pressure controlled mechanism for advancing 110 and retracting said milling devices with respect to the ends of said tube.

4. In a tube-milling machine of the character described, the following elements in combination:—a framework which embodies 115 a longitudinal bed,—means for successively feeding to said bed tubes to be milled,—means for receiving above the bed each tube as fed, fluid pressure actuated means for securing it in position to have both of its ends simultaneously milled,—means upon the bed for simultaneously milling both ends of a tube as received and secured in position above said bed,—means for actuating the milling means to effect their operation simultaneously but in reverse directions upon both ends of a tube,—and means for successively releasing the tube-securing means to permit of the successive removal of each milled tube 120 from the machine. 125 130

5. In a tube-milling machine of the character described, the following elements in combination:—a framework which embodies a longitudinal bed,—means for successively feeding to said bed tubes to be milled,—means for receiving above the bed each tube as fed, fluid pressure actuated means for securing it in position to have both of its ends simultaneously milled,—means upon 5
- 10 the bed for simultaneously milling both ends of a tube as received and secured in position above said bed,—means for endwise, longitudinal, relative adjustment of the milling means,—means for actuating the milling 10
- 15 means to effect their operation simultaneously but in reverse directions upon both ends of a tube,—and means for successively releasing the tube-securing means to permit of the successive removal of each milled tube 15
- 20 from the machine.
6. In a tube-milling machine of the character described, the following elements in combination:—a framework which embodies a supporting bed,—means for successively 20
- 25 feeding to said bed tubes to be milled,—guttered clamp blocks upon the bed to receive the tubes as fed,—fluid pressure actuated means to secure the tubes upon said clamp blocks,—separated milling heads, oppositely 25
- 30 disposed upon the bed in axial alignment with each other, to mill the ends of the tubes,—means for reversely rotating the milling heads,—and means for successively releasing the tube-securing means to permit 30
- 35 of the removal of each tube from the machine.
7. In a tube-milling machine of the character described, the following elements in combination:—a framework which embodies a supporting bed,—means for successively 40
- 40 feeding to said bed tubes to be milled,—guttered clamp blocks upon the bed to receive the tubes as fed,—fluid pressure actuated means to secure the tubes upon said 40
- 45 clamp blocks,—separated milling heads, oppositely disposed upon the bed in axial alignment with each other, to mill the ends of the tubes,—means for endwise, longitudinal, relative adjustment of the milling 45
- 50 means,—means for reversely rotating the milling heads,—and automatic means for removing the tubes from the receiving means, and automatic means for discharging the 50
- 55 milled tubes from the machine.
8. In a tube-milling machine of the character described, the following elements in combination:—a framework which embodies a longitudinal bed,—means for successively feeding to said bed tubes to be milled,— 55
- 60 means for receiving the tubes to be milled on the bed,—fluid-controlled means for securing the tubes upon the receiving means,—means upon the bed for simultaneously and reversely milling both ends of the tubes,— 60
- 65 fluid-controlled means for forcing into 65
- action the milling means,—means for successively releasing the tubes from the receiving means,—and means for successively discharging the milled tubes from the machine. 70
9. In a tube-milling machine of the character described, the following elements in combination:—a framework which embodies a longitudinal bed,—means for successively feeding to said bed tubes to be milled,—means for receiving the tubes to 75
- 75 be milled on the bed,—fluid-controlled pistons for securing the tubes upon the receiving means,—milling heads oppositely disposed upon the bed in axial alignment with each other,—means for rotating said 80
- 80 milling heads in reverse directions,—fluid-controlled pistons for forcing into action the milling heads,—means for successively releasing the tube from the receiving means,—and means for successively discharging the milled tubes from the machine. 85
10. In a tube-milling machine of the character described, the following elements in combination:—a framework which embodies a longitudinal bed,—guiding devices upon which tubes are placed to be delivered to the bed,—tube-receiving devices upon which the tubes are successively placed from the guiding devices,—a pair of vertical cylinders erected upon and near the ends of the bed above the tube-receiving devices, and each provided with a vertical piston carrying clamping means for securing the tubes upon the tube-receiving devices,—a 90
- 90 pair of horizontal cylinders erected upon and near the ends of the bed beyond the receiving devices and the vertical cylinders, and each provided with a horizontal piston provided at its outer end with a milling head,—milling heads axially aligned with the horizontal pistons and rotatably connected therewith,—means for occasioning the predetermined cyclical operation of the vertical pistons and of the horizontal pistons,—and means for occasioning the rotation of the milling heads. 95
11. In a tube-milling machine of the character described, the following elements in combination:—a framework which embodies a longitudinal bed,—means by which tubes are successively delivered to clamp blocks upon the bed,—clamp blocks upon the bed,—a pair of oppositely disposed, correspondent, vertical cylinders erected upon the bed near the ends thereof and beyond the clamp blocks,—vertical pistons within the vertical cylinders, provided at their downwardly-extending ends with clamping blocks which co-operate with the clamp blocks on the bed to secure a tube in position,—a pair of oppositely-disposed, correspondent, horizontal cylinders erected upon and near the ends of the bed beyond both the clamp blocks and the vertical cylinders,—horizontal pistons within the horizontal cylinders. 100
- 100
- 115
- 120
- 125
- 130

zontal cylinders, provided at their outwardly-extending ends with milling head-shafts in alignment and rotatable connection therewith,—milling head shafts,—milling heads connected with the outer ends of the milling head shafts,—fluid-controlled means for occasioning the predetermined cyclical operation of said vertical pistons and said horizontal pistons,—and means 10 for occasioning the rotation of the milling heads.

12. In a tube-milling machine of the character described, the following elements in combination:—a framework which embodies a longitudinal bed,—means by which tubes are successively delivered to tube-receiving means upon the bed,—tube-receiving means upon the bed,—a pair of vertical cylinders erected upon and near the ends 15 of the bed above the tube-receiving means, and provided with tube-releasing devices,—vertical pistons within the vertical cylinders, provided at their downwardly extending ends with clamping devices which 20 co-operate with the tube-receiving means on the bed to secure a tube in position,—a pair of oppositely disposed, correspondent, horizontal cylinders erected upon and near the ends of the bed beyond both the tube-receiving means and the vertical cylinders,—horizontal pistons within the horizontal cylinders, provided at their outwardly extending ends with milling head shafts connected with them in rotatable and aligned 25 relationship,—milling head shafts,—milling heads connected with the outer end of the milling head shafts,—means for occasioning the opposite rotation of the milling heads,—and fluid controlled means for occasioning the predetermined cyclical operation 30 of said vertical pistons and said horizontal pistons.

13. A tube-milling machine of the character described, in which are combined with a supporting bed,—means for successively feeding tubes to be milled,—means for receiving each tube as fed and securing it in position to have both of its ends simultaneously milled,—means for simultaneously 45 milling both ends of a tube as secured in position,—means for successively removing from the machine each milled tube,—and a fluid-controlled means for occasioning the predetermined cyclical operation of the 50 means for receiving and securing each tube, of the means for simultaneously milling both ends of the tube and of the means for successively removing from the machine each milled tube.

14. A tube-milling machine of the character described, in which are combined with a supporting bed,—means for successively delivering to said bed tubes to be milled,—tube-receiving devices upon the bed,—tube-milling devices,—oppositely disposed verti-

cal cylinders,—vertical pistons within said cylinders provided with means for clamping the tubes upon the tube-receiving devices,—oppositely disposed horizontal cylinders,—horizontal pistons within said cylinders provided with tube-milling devices,—and fluid controlled means for occasioning the predetermined cyclical operation of said vertical pistons and of said horizontal pistons. 75

15. A tube-milling machine of the character described, in which are combined with a supporting bed,—means for successively delivering to said bed tubes to be milled,—tube-receiving devices upon the bed,—tube-milling devices,—oppositely disposed vertical cylinders,—pistons within said cylinders provided with means for clamping the tubes upon the tube-receiving devices,—oppositely disposed horizontal cylinders,—horizontal pistons within said cylinders provided with tube-milling devices,—fluid-controlled means for occasioning the predetermined cyclical operation of said vertical pistons and of said horizontal pistons,—and means for rotating the tube-milling devices. 80 85 90

16. A tube-milling machine of the character described, in which are combined with a supporting bed,—means for successively delivering to said bed tubes to be milled,—tube-receiving devices upon the bed,—tube-milling devices,—oppositely disposed vertical cylinders provided with tube-releasing devices,—vertical pistons within said cylinders provided with means for clamping the tubes upon the tube-receiving devices,—oppositely disposed horizontal cylinders,—horizontal pistons within said cylinders operating to rotate the tube-milling devices,—and fluid-controlled means for occasioning the predetermined cyclical operation of said vertical pistons and of said horizontal pistons. 100 105

17. A tube-milling machine of the character described, in which are combined with a supporting bed,—means for successively delivering to said bed tubes to be milled,—tube-receiving devices upon the bed,—tube-milling devices,—oppositely disposed vertical cylinders provided with tube-releasing devices,—vertical pistons within said cylinders provided with means for clamping the tubes upon the tube-receiving devices,—oppositely disposed horizontal cylinders,—horizontal pistons within said cylinder operating to rotate the tube milling devices,—fluid-controlled means for occasioning the predetermined cyclical operation of said vertical piston and of said horizontal pistons,—and means for rotating the tube-milling devices. 110 115 120 125

18. A tube-milling machine of the character described, in which are combined with a supporting bed,—means for successively

delivering to said bed tubes to be milled,—tube-receiving devices upon the bed,—tube-milling devices,—oppositely disposed vertical cylinders,—vertical pistons within said cylinders provided with means for clamping the tubes upon the tube-receiving devices,—oppositely disposed horizontal cylinders,—horizontal pistons within said cylinders connected with tube-milling devices,—means for rotating the tube-milling devices,—a valve-controlled pipe line system in communication with a source of motive fluid supply, and connected with both ends of the vertical cylinders and with both ends of the horizontal cylinders,—and a rotary valve applied to said pipe line system and adapted in calculated order to occasion the operation of the motive fluid, first upon the upper ends of the vertical cylinders, next, upon the outer ends of the horizontal cylinders, next upon the inner ends of the horizontal cylinders, and last, upon the lower ends of the vertical cylinders.

19. A tube-milling machine of the character described, in which are combined with a supporting bed,—means for successively delivering to said bed tubes to be milled,—tube-receiving devices upon the bed,—tube-milling devices,—oppositely disposed vertical cylinders,—means for rotating the tube-milling devices,—vertical pistons within said cylinders provided with means for clamping the tubes upon the tube-receiving devices,—oppositely disposed horizontal cylinders,—horizontal pistons within said cylinders connected with the tube-milling devices,—means for rotating said tube-milling devices,—a valve-controlled pipe line system in communication with a source of motive fluid supply, and connected with both ends of the vertical cylinders and with both ends of the horizontal cylinders,—a rotary eight-way valve applied to said pipe line system and adapted in calculated order of admission and exhaust of motive fluid, to occasion the operation of said fluid, first, simultaneously upon the upper ends of the vertical cylinders, next, upon the outer ends of the horizontal cylinders, next upon the inner ends of the horizontal cylinders, and, last, upon the lower ends of the vertical cylinders, as hereinbefore described,—and mechanism connected with the means for rotating the tube-milling devices for occasioning the predetermined requisite rotation of said valve.

20. A tube-milling machine of the character described, in which are combined with a supporting bed,—means for successively delivering to said bed tubes to be milled,—tube-receiving devices upon the bed,—tube-milling devices,—oppositely disposed vertical cylinders,—means for rotating the tube-milling devices,—vertical pistons within said cylinders provided with means for clamping the tubes upon the tube-receiving devices,—oppositely disposed horizontal cylinders,—horizontal pistons within said cylinders connected with the tube-milling devices,—means for rotating said tube-milling devices,—a valve-controlled pipe line system in communication with a source of motive fluid supply, and connected with both ends of the vertical cylinders and with both ends of the horizontal cylinders,—a rotary eight-way valve applied to said pipe line system and adapted in calculated order of admission and exhaust of motive fluid, to occasion the operation of said fluid, first, simultaneously upon the upper ends of the vertical cylinders, next, upon the outer ends of the horizontal cylinders, next upon the inner ends of the horizontal cylinders, and, last, upon the lower ends of the vertical cylinders, as hereinbefore described,—and mechanism connected with the means for rotating the tube-milling devices for occasioning the predetermined requisite rotation of said valve.
